United States Patent Office

Des. 215,971
Patented Nov. 11, 1969

215,971

VERTICAL LIFT AIRCRAFT

William N. Rosta, Fort Worth, Tex., assignor to The VLM Corporation, Fort Worth, Tex., a corporation of Delaware

Filed Mar. 4, 1969, Ser. No. 16,030

Term of patent 14 years

Int. Cl. D12—07

U.S. Cl. D71—1

FIG. 1

FIG. 2

FIG. 3

FIGURE 1 is a top plan view of a vertical lift aircraft showing my new design;

FIGURE 2 is a side elevation view thereof;

FIGURE 3 is a bottom plan view thereof.

The sides of the vertical lift aircraft not shown are substantially the same in appearance as the sides shown.

I claim:

The ornamental design for a vertical lift aircraft, as shown and described.
